UNITED STATES PATENT OFFICE.

LEAH G. MILKES, OF MINNEAPOLIS, MINNESOTA, ASSIGNOR TO VENUS MANUFACTURING COMPANY, OF MINNEAPOLIS, MINNESOTA, A CORPORATION OF MINNESOTA.

CHILD'S OVERGARMENT.

Application filed February 10, 1923. Serial No. 618,298.

To all whom it may concern:

Be it known that I, LEAH G. MILKES, a citizen of the United States, residing at Minneapolis, in the county of Hennepin and State of Minnesota, have invented certain new and useful Improvements in Children's Overgarments; and I do hereby declare the following to be a full, clear, and exact description of the invention, such as will enable others skilled in the art to which it appertains to make and use the same.

My invention relates to what is generally designated as outdoor garments for children, and is particularly designed as an improvement on the garment disclosed and broadly claimed in my prior Patent No. 1,292,351, of date January 21, 1919. The salient feature of novelty involved in my prior patent was a flap projecting from the lower edge of the back of the garment and arranged to be folded upward and over the lapped front flaps and to be secured in different adjustments so as to increase the length of the garment to keep pace with the growth of the child, or figuratively speaking, to cause the garment to grow in length as the child grows. Broadly, the above feature is present in this improved garment. In the first form of the garment, however, the depending flap or extension from the back of the garment was only as wide as the garment, and when it was adjusted to a lowered position, openings were formed at the extended sides, through which the feet of the child might project. This latter noted feature is remedied in the present garment by making the depending flap materially wider than the width of the garment, thereby adapting the ends of the depending flap, when turned upward, to be secured to the body of the garment at the back thereof. With this arrangement, the backturned portions of the flap always keep the sides of the garment closed even when the flap is lowered to give the garment maximum length and, moreover, the fastening devices, such as buttons and button holes, are placed at the back of the garment and, hence, not visible from the front of the garment and this gives the garment a neater front appearance, which is highly important because a child wearing

this garment will usually be lying or sitting down.

The garment of the above character is adapted for use, first by the small infant, and as the child grows, the garment may be readily adjusted to its growth. As the garment is intended chiefly as an outdoor garment, it is of the utmost importance that it be a completely and well closed garment so that the child's feet cannot get out of the garment and the cold air cannot get into the garment. The above described novel arrangement accomplishes these results by the most simple kind of means, which add nothing to the cost of the garment.

In the accompanying drawings, which illustrate a commercial form of the garment, like characters indicate like parts throughout the several views.

Referring to the drawings:

Fig. 1 is a front elevation showing the complete garment adjusted to its shortest length;

Fig. 2 is a rear elevation showing the lower portion only of the garment;

Fig. 3 is a front elevation showing the lower portion of the garment with the back flap extension turned down;

Fig. 4 is a front elevation showing the lower portion of the garment with the back flap secured in its lowest adjustment to give maximum length to the garment; and

Fig. 5 is a rear elevation of that portion of the garment shown in Fig. 4, adjusted as shown in said views.

The body 6 of the garment is formed with overlapping front flaps secured by the customary buttons and button holes 7, and the said body is shown as provided with an attached hood 8 and with sleeves 9, the construction of which, however, need not for the purposes of this case be further considered. At the back of the body of the garment is the depending approximately rectangular extension flap 10, which, as stated, in transverse length is considerably longer than the width of the garment, (see particularly Fig. 3, which shows said flap turned down). This flap is adapted to be secured to the body of the garment by separable fasteners, preferably buttons and button holes. At the ends,

said flap 10 is provided with button holes 11, 12, and 13, and, at its lower edge, it is provided with button holes 14. On the back of the garment are buttons 15, 16, and 17 adapted

5 to be buttoned into the button holes 11, 12, and 13 when the garment is adjusted for its shortest length, as shown in Figs. 1 and 2. By reference particularly to Fig. 2, it will be noted that the ends of the extension flap 10 are folded against the back of the garment and, by reference to Fig. 1, it will be noted that the said buttons and button holes and the ends of the flap 10 are invisible from the front of the garment. The 10 front flaps of the garment are provided with buttons 18 that are adapted to be buttoned into the button holes 14 when the garment is adjusted for its shortest length, as shown in Figs. 1 and 2.

15 When the garment is to be increased to its intermediate length, the flap 10 will be turned up and the button holes 12 and 13 will then be buttoned onto the buttons 15 and 16 and the buttons 17 may then be cut 20 off or left on the garment, as desired. The buttons 18 should then also be properly lowered to align with the new position of the button holes 14.

25 When the garment is to be given its maximum length, the flap 10 is turned up only far enough to permit button holes 13 to be engaged with the lower buttons 15 and the buttons 16 may then be cut off or left on, as desired. The buttons 18 should then be 30 again lowered to the new position of the button holes 14. In all of these positions, as is evident, the backturned ends of the flap 10 positively close the extended sides of the garment so that the child's feet cannot 35 project from the garment and cold air cannot get into the garment. Of course, the garment may be extended on the plan above described by any desired number of steps, but for practical purposes, the three steps are 40 thought sufficient. Of course, when the child has entirely outgrown the garment with the flap 10 attached, and has learned to walk, said flap may be cut off and the garment then 45 used as an open bottom garment.

50 Of course, the garment may be made of

any suitable material, and in practice it will usually be made of eiderdown, canton flannel, or other heavy and warm soft cloth.

What I claim is:

1. A child's garment having front flaps 55 and a centrally located extension flap extended downward from the back of the garment and turned upward over the lapped front flaps, said extension flap having a transverse length greater than the width of 60 said garment, the ends of said extension flap and the back of the garment being provided with cooperating separable fastening elements.

2. A child's garment having front flaps 65 and a centrally located extension flap extended downward from the back of the garment and turned upward over the lapped front flaps, said extension flap having a transverse length greater than the width of 70 said garment, the ends of said extension flap and the back of the garment being provided with cooperating separable fastening elements, and the edge of said extension flap 75 and the front flaps of the garment being provided with cooperating separable fastening elements for securing said flap in its upturned position.

3. A child's garment having front flaps 80 and a centrally located extension flap extended downward from the back of the garment and turned upward over the lapped front flaps, said extension flap having a transverse length greater than the width of 85 said garment, the ends of said extension flap and the back of the garment being provided with cooperating separable fastening elements, and the edge of said extension flap 90 and the front flaps of the garment being provided with cooperating separable fastening elements for securing said flap in its upturned position, and the said fasteners at the front and back of the garment permitting 95 said extension flap to be secured in different upturned positions to vary the length of the garment while maintaining closed joints at the lower side portions of the garment.

In testimony whereof I affix my signature.

LEAH G. MILKES.
